LEG FOR A SERVING UTENSIL

Robert Haber, 834 Edward St., Baldwin, N.Y. 11510

Filed June 18, 1973, Ser. No. 370,791

Term of patent 14 years

Int. Cl. D7—01

U.S. Cl. D7—39

FIG. 1 is a front elevational view of a leg for a serving utensil showing my new design;

FIG. 2 is a left side elevational view;

FIG. 3 is a top plan view; and

FIG. 4 is a bottom plan view.

The rear of the leg for a serving utensil is plain and unornamented.

I claim:

The ornamental design for a leg for a serving utensil, substantially as shown.
